United States Patent Office

Des. 207,017
Patented Feb. 21, 1967

207,017

BUTTER DISH

Roger Dulac, 15-17 Ave. Rapp, Paris, France
Filed Oct. 6, 1965, Ser. No. 87,342

Claims priority, application France Apr. 8, 1965

Term of patent 3½ years

(Cl. D44—5)

Fig. 2

I claim:

The ornamental design for a butter dish, substantially as shown.
